United States Patent Office.

CHARLES G. WATERBURY, OF NEW YORK, N. Y.

Letters Patent No. 69,517, dated October 1, 1867.

IMPROVED WOODEN PAVEMENT.

The Schedule referred to in these Letters Patent and making part of the same.

TO ALL WHOM IT MAY CONCERN:

Be it known that I, CHARLES G. WATERBURY, of New York, in the county of New York, and State of New York, have invented a new and useful improvement in Wooden Pavements; and I do hereby declare that the following is a full, clear, and exact description thereof, reference being had to the accompanying drawings, in which—

Figure 1 is a plan view of a section of a pavement constructed in accordance with my invention.

Figure 2 is a plan view of one of the blocks composing the pavement, and

Figure 3 is an end view of the same.

Figure 4 is a bottom view of the pavement.

Figure 5, a side elevation of the same, and

Figure 6 an end view.

Figure 7 is a top view of one of the movable strips.

Similar letters of reference indicate like parts in all the figures.

My invention relates to that class of pavements known as wooden pavements, and it consists in so arranging and fastening the same from the top that each block of which it is composed has a bearing upon its adjoining six by means of movable strips horizontally laid in after the blocks have been placed upon their bed, and so fastened down by bolts or their equivalents, and which may be withdrawn, so that one or more blocks may be taken up for the purpose of repairing water-mains, sewers, or gas pipes, and the same be replaced again with ease and facility, and with all its former strength and bearings.

To enable others to make and use my invention, I will now proceed to describe the same by reference to the accompanying drawings.

A are the wooden blocks, having two projections B on each side, extending about half way up the blocks A. These projections vary in size, the larger ones being twice as long as the others, and are placed on opposite sides and opposite ends of the block, as seen in figs. 2 and 4, so that, when the pavement is laid, the blocks will fit into one another, and each have a bearing on and be supported by six adjoining ones. C are removable strips, which rest upon the part of the projections B, and are held firmly down upon said projections by means of bolts or spikes D driven into the sides of the blocks A. These strips are of about the same length as the blocks, and are mitred at each end for the purpose of insuring a perfect fit, as seen in fig. 7. One end of each of the blocks A is cut away, forming a projection, E, as seen in figs. 2 and 3, which projections are flush with the upper surfaces of strips C, so that, when the pavement is laid, there will be an opening between the ends of the blocks for the purpose of driving in the bolts.

The mode of laying the pavement is as follows: The road-bed having been concreted with suitable material, the blocks are placed thereon and fitted into each other, as seen in fig. 4, each block resting against and being supported by six adjoining ones. The desired distance or number of blocks being thus laid, the strips C are inserted in the spaces between the blocks, formed by the projections B, and the bolts D driven into the blocks, in the manner shown in fig. 1, holding all the blocks firmly together, and rendering it impossible to remove any of them without first withdrawing the bolts D and removing the strips C. The spaces C' between the blocks may afterwards be filled up with tar, pitch, gravel, or other suitable substances.

If it is desired to remove any portion of the pavement for the purpose of repairing sewers or water-mains, or for any other purpose, the tar or pitch filling is dug out, and the bolts or spikes D withdrawn by any suitable instrument, and the strips C removed, when the blocks may be easily taken out. They are afterwards replaced, as above set forth, and will possess all their former strength and bearing. For permanent pavements the strips C may be of any length convenient, they being made in sections only for the purpose of facilitating the work of taking up and relaying.

By making the projections B rise flush with the end projections E the strips C may be dispensed with, in which case the bolts D will be driven in immediately above the shoulders formed by projections B, and bear directly upon them, in like manner as they bear upon the strips C when the latter are used.

Having thus fully described my invention, and the manner in which the same is or may be carried into effect, what I claim as my invention, and desire to secure by Letters Patent, is—

1. The blocks A, with their projections B and E, constructed and arranged substantially as and for the purpose set forth.

2. In combination with the blocks A, having projections B and E, I claim the movable strips C and bolts D, substantially as and for the purpose set forth.

3. In combination with the blocks A, having projections B and E, I claim the bolts D, with or without the strips C, substantially as and for the purpose described.

C. G. WATERBURY.
